ROTARY TOOL AND ATTACHMENT
THEREFOR

Frank P. Granat, Woodside, Long Island, N. Y.

Application October 1, 1940, Serial No. 359,186

7 Claims. (Cl. 145—67)

This invention relates to rotary tools and attachments therefor.

One of the objects of my invention is to provide a highly improved manually rotatable tool and attachment therefor wherein a turning torque may be optionally applied about an axis coincident with or transverse to the axis of the tool handle.

Another object of my invention is to provide a rotary tool and attachment of the character described wherein the handle may be selectively spaced at varying distances from the turning axis which is disposed transversely to the axis of the handle.

Another object of my invention is to provide a manually actuatable rotary tool and attachment therefor by means of which a varying turning torque may be applied.

Another object of my invention is to provide a rotary tool and attachment wherein means are provided for steadyng the rotary operative member of the tool.

Another object of my invention is to provide a rotary tool and attachment of the character described which shall be simple and economical to manufacture, shall be rugged in construction, and highly efficient for the purposes set forth.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing in which are shown several embodiments of my invention,

Fig. 1 is a side sectional view of a screw driver and screw driver attachment embodying my invention;

Fig. 2 is a plan view thereof;

Fig. 3 is a sectional view taken substantially along the line 3—3 of Fig. 1;

Fig. 4 is a sectional view taken substantially along the line 4—4 of Fig. 1;

Fig. 5 is an enlarged sectional view taken substantially along the line 5—5 of Fig. 1; and

Fig. 6 is a perspective view of an auxiliary socket tool attachment adapted to be used with my invention.

Referring now to the drawing, 10 is a screw driver comprising a handle 11 within which is disposed one end of a shank 12 having a screw driver blade 13 formed at the other end thereof. For detachably securing the shank 12 to the handle 11 an axial bore 14 is provided in the handle 11, said bore being shaped similarly to the contours of the shank 12. Said handle 11 is also provided with a pin 15 having a reduced portion 16 which is adapted to be received within

an aperture 17 in the shank 12. The upper end of the pin 15 is attached to one end of a leaf spring 18 by means of a rivet head 19 integral with the pin 15. The other end of said spring 18 is suitably fixed to the handle 11 as by a rivet 20. If desired a small depression 21 may be provided on the portion of the handle underlying the free end of the spring 18 in order to facilitate the insertion of a fingernail beneath the free end of the spring, when it is desired to raise the pin 15 and release the shank 12.

In accordance with my invention I provide a member slidably and rotatably mounted on the shank 12 which may comprise a two-part casing 25 held in assembled relationship by a pair of rivets 26. The casing is prevented from slipping off the shank by the width of the blade 13 and by the handle.

Associated with said member is means for detachably holding and rotating an auxiliary rotary tool about an axis angularly disposed relative to the shank 12. Said means may comprise a pair of meshing bevel gears 27 and 28 rotatably and non-slidably held in recesses formed for this purpose in the casing 25. One of said gears 27 is adapted to be rotated by the shank 12, the other gear 28 being adapted to rotate an auxiliary rotary tool. In order to cause the bevel gear and shank 12 to rotate together in any position of the casing 25 along the shank 12, the gear 27 is provided with a central bore 29 of non-circular cross-section which corresponds in outline to the transverse profile of the shank 12.

In the embodiment of my invention herein shown, both the bore and the shank are square. However, any other non-circular outline may be employed, such as for example splined, triangular or oval, or a circular shank may be used if provided with a key. The bevel gear 28 is also provided with a central aperture 30 of non-circular contour within which is received a stub shank 31 having an auxiliary screw driver blade 32 formed on the outer end thereof. Said aperture 30 and shank 31 are also of mating non-circular contour so that the gear 28 and screw driver blade 32 will rotate together. Thus, when the shank 12 is turned by means of the handle 11 while the casing 25 is held stationary, both the screw driver blades 13 and 32 will rotate. To facilitate gripping of the casing 25, oppositely disposed faces thereof may be slightly concaved, as indicated at 33.

While the auxiliary tool has been shown as turning about an axis perpendicular to that of the shank, other angles, such as 45°, may be employed.

In order to retain the casing 25 in any desired position along the shank 12, suitable means may be provided to cause frictional engagement between the casing 25 and the shank 12. Said

means may comprise a split spring ring 34 disposed in an annular groove 35 formed in the shank of the bevel gear 27 around the bore 30. It will thus be seen that the portions of the spring ring 34 adjacent the corners of the square bore 29 will frictionally grip and be constricted about the shank 12 so as to cause the gear 27 and associated casing 25 to remain at any point along the length of the shank 12 until the casing 25 is manually forced into a new position. Similar means indicated by primed numerals (Fig. 5) are provided in the shank of the bevel gear 28 in order to frictionally hold the shank 31 and the auxiliary screw driver blade 32 therein.

My device may be employed in several ways. Thus, the blade 13 may be caused to engage a slot in a screw and the handle rotated in the well known fashion to turn the screw. In order to facilitate this operation, the casing 25 may be slid down the shank 12 and disposed adjacent the blade 13 so that while the blade 13 is being turned the concave surface 33 of the casing may be gripped between the thumb and index fingers to steady the blade 13 and prevent it from slipping out of the slot.

Also, when a screw is in an awkward position and insufficient room is present to insert an ordinary screw driver, the auxiliary blade 32 may be inserted in the screw slot, the upper edge of the casing 25 pressed down towards the screw, and the handle 11 slid to a position where it can be conveniently turned. Then when the handle 11 is rotated the blade 32 and engaged screw slot will also be caused to rotate.

In addition, my novel screw driver and attachment may be employed to obtain an unusually high turning torque much greater than can be obtained by merely rotating the handle of the screw driver. In accordance with this feature of my screw driver the screw driver blade 32 is placed in a screw while the said handle is tightly gripped to prevent it from rotating about its own axis. This method feature may be employed when it is desired to loosen a tight screw or to tighten a screw in its final position.

If desired, a socket wrench 36 or any other rotary tool well known to the art may be provided with a shank 37 (Fig. 6) and thus employed in place of the screw driver blade 32.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A rotary tool comprising an elongated shank, an auxiliary tool adapted to rotate about an axis transverse to the longitudinal axis of said shank, means to rotate said shank, a member slideable along and rotatable relative to said shank, said auxiliary tool being movable with said member and rotatable relative thereto about said transverse axis, and means carried by said member to rotate said auxiliary tool, said last named means being driven by said shank upon rotation thereof while said member is prevented from revolving with said shank by manually holding said member.

2. A rotary tool comprising an elongated shank, means to rotate said shank, an auxiliary tool, and a driving train operatively engaging said auxiliary tool at one end of said train, the opposite end 5 of said train operatively engaging said shank and being slidably along the longitudinal axis of said shank whereby rotation of said shank will cause rotation of said auxiliary tool at any position of said tool along the longitudinal axis of said shank.

3. A rotary tool comprising an elongated shank, means to rotate said shank, an auxiliary tool adapted to rotate about an axis transverse to the longitudinal axis of said shank, a driving train, 15 and a housing for said driving train, said housing being slidably and rotatably mounted on said shank, said driving train operatively engaging said auxiliary tool at one end, the opposite end of said driving train operatively engaging said shank and being slidable along the longitudinal axis of said shank whereby rotation of said shank when said housing is manually held will cause rotation of said auxiliary tool at any position of said tool along the longitudinal axis of said shank.

4. A rotary tool comprising an elongated shank, means to rotate said shank, an auxiliary tool adapted to rotate about an axis transverse to the longitudinal axis of said shank, a driving train, and a housing for said driving train, said housing being slidably and rotatably mounted on said shank, said driving train operatively engaging said auxiliary tool at one end, the opposite end 30 of said driving train operatively engaging said shank and being slidable along the longitudinal axis of said shank, the first named end of said driving train being revolvable with said housing about said shank whereby rotation of said shank when said housing is manually held will cause rotation of said auxiliary tool at any position of said auxiliary tool along the longitudinal axis of said shank.

5. A rotary driver tool comprising an elongated shank, an auxiliary driver tool, means to actuate 45 said auxiliary driver tool from said shank, said actuating means being slidably but non-rotatably mounted on said shank, said auxiliary tool being slidable with said actuating means.

6. A rotary tool comprising an elongated shank, 50 an auxiliary tool adapted to be rotated about an axis transverse to the longitudinal axis of said shank, a housing slidably and rotatably mounted on said shank, a gear slidably and non-rotatably mounted on said shank and journalled in said housing, a second gear journalled in and mounted for rotation with said housing, said second gear being driven by said first gear, and means driven by said second gear to rotate said auxiliary tool.

7. A rotary tool comprising an elongated shank, 55 an auxiliary tool adapted to rotate about an axis transverse to the longitudinal axis of said shank, a bevel gear slidably and non-rotatably mounted on said shank, a housing rotatably mounted on said bevel gear, a second bevel gear meshing with said first bevel gear, said second bevel gear being journalled in and mounted for rotation with said housing, said second bevel gear having an axial opening adapted to operatively receive said auxiliary tool, and means carried by said second bevel gear and projecting into said opening to releasably retain said auxiliary tool in said second gear.

FRANK P. GRANAT.
